(57) **CLAIM**

The ornamental design for a valve, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a valve according to a first embodiment of the present invention;

FIG. 2 is a left side view of the valve of FIG. 1;

FIG. 3 is a right side view of the valve of FIG. 1;

FIG. 4 is a front view of the valve of FIG. 1;

FIG. 5 is a rear view of the valve of FIG. 1;

FIG. 6 is a top view of the valve of FIG. 1;

FIG. 7 is a bottom view of the valve of FIG. 1;

FIG. 8 is a perspective view of a valve according to a second embodiment of the present invention;

FIG. 9 is a left side view of the valve of FIG. 8;

FIG. 10 is a right side view of the valve of FIG. 8;

FIG. 11 is a front view of the valve of FIG. 8;

FIG. 12 is a rear view of the valve of FIG. 8;

FIG. 13 is a top view of the valve of FIG. 8;

FIG. 14 is a bottom view of the valve of FIG. 8;

FIG. 15 is a perspective view of a valve according to a third embodiment of the present invention;

FIG. 16 is a left side view of the valve of FIG. 15;

FIG. 17 is a right side view of the valve of FIG. 15;

FIG. 18 is a front view of the valve of FIG. 15;

FIG. 19 is a rear view of the valve of FIG. 15;

FIG. 20 is a top view of the valve of FIG. 15;

FIG. 21 is a bottom view of the valve of FIG. 15;

FIG. 22 is a perspective view of a valve according to a fourth embodiment of the present invention;

FIG. 23 is a left side view of the valve of FIG. 22;

FIG. 24 is a right side view of the valve of FIG. 22;

FIG. 25 is a front view of the valve of FIG. 22;

FIG. 26 is a rear view of the valve of FIG. 22;

FIG. 27 is a top view of the valve of FIG. 22;

(Continued)

FIG. 28 is a bottom view of the valve of FIG. 22;
 FIG. 29 is a perspective view of a valve according to a fifth embodiment of the present invention;
 FIG. 30 is a left side view of the valve of FIG. 29;
 FIG. 31 is a right side view of the valve of FIG. 29;
 FIG. 32 is a front view of the valve of FIG. 29;
 FIG. 33 is a rear view of the valve of FIG. 29;
 FIG. 34 is a top view of the valve of FIG. 29;
 FIG. 35 is a bottom view of the valve of FIG. 29;
 FIG. 36 is a perspective view of a valve according to a sixth embodiment of the present invention;
 FIG. 37 is a left side view of the valve of FIG. 36;
 FIG. 38 is a right side view of the valve of FIG. 36;
 FIG. 39 is a front view of the valve of FIG. 36;
 FIG. 40 is a rear view of the valve of FIG. 36;
 FIG. 41 is a top view of the valve of FIG. 36;
 FIG. 42 is a bottom view of the valve of FIG. 36;
 FIG. 43 is a perspective view of a valve according to a seventh embodiment of the present invention;
 FIG. 44 is a left side view of the valve of FIG. 43;
 FIG. 45 is a right side view of the valve of FIG. 43;
 FIG. 46 is a front view of the valve of FIG. 43;
 FIG. 47 is a rear view of the valve of FIG. 43;
 FIG. 48 is a top view of the valve of FIG. 43;
 FIG. 49 is a bottom view of the valve of FIG. 43;
 FIG. 50 is a perspective view of a valve according to an eighth embodiment of the present invention;
 FIG. 51 is a left side view of the valve of FIG. 50;
 FIG. 52 is a right side view of the valve of FIG. 50;
 FIG. 53 is a front view of the valve of FIG. 50;
 FIG. 54 is a rear view of the valve of FIG. 50;
 FIG. 55 is a top view of the valve of FIG. 50;
 FIG. 56 is a bottom view of the valve of FIG. 50;
 FIG. 57 is a perspective view of a valve according to a ninth embodiment of the present invention;
 FIG. 58 is a left side view of the valve of FIG. 57;
 FIG. 59 is a right side view of the valve of FIG. 57;
 FIG. 60 is a front view of the valve of FIG. 57;
 FIG. 61 is a rear view of the valve of FIG. 57;
 FIG. 62 is a top view of the valve of FIG. 57; and,
 FIG. 63 is a bottom view of the valve of FIG. 57.
 The broken lines are for the purpose of illustrating portions of the valve and form no part of the claimed design.
